ELECTRIC SPRAYER OR THE LIKE

Theodor Krebs, Kreuzlingen, Switzerland

Application June 5, 1956, Serial No. 41,770

Claims priority, application Switzerland February 7, 1956

Term of patent 14 years

(Cl. D62—2)

Fig. 3

Fig. 1 is a view in side elevation showing a sprayer embodying my new design.

Fig. 2 is a top plan view of the sprayer; and,

Fig. 3 is a view in perspective thereof.

The opposite side of the sprayer illustrated in Figs. 1 and 3 is identical to the side shown.

I claim:

The ornamental design for an electric sprayer or the like, substantially as shown and described.
